UNITED STATES PATENT OFFICE.

JOHN C. MABRY, OF KANSAS CITY, MISSOURI.

GARMENT SUPPORTER.

Application filed June 17, 1922. Serial No. 568,991.

To all whom it may concern:

Be it known that I, JOHN C. MABRY, a citizen of the United States, residing at Kansas City, in the county of Jackson and 5 State of Missouri, have invented a certain new and useful Improvement in Garment Supporters, of which the following is a specification.

My invention relates to improvements in 10 garment supporters. It is particularly well adapted for use as the trouser attaching means on suspenders.

The object of my invention is to provide 15 a garment supporter which is simple, cheap, strong, durable, not liable to get out of order and which may be easily and quickly attached to or detached from the trousers, when the suspenders are worn either inside or at the outside of the shirt.

20 My invention provides further novel means for securing the garment engaging pin to the member which carries the pin.

The novel features of my invention are hereinafter fully described and claimed.

25 In the accompanying drawing, which illustrates the preferred embodiment of my invention,

Fig. 1 is a reduced view showing some of 30 my improved supporters attached to a pair of suspenders.

Fig. 2 is an enlarged front elevation of my improved garment supporter shown in the garment engaging position and attached to a portion of a suspender.

35 Fig. 3 is a view similar to Fig. 2 with the pin supporting member shown in the release position.

Fig. 4 is an enlarged vertical sectional view on the line 4—4 of Fig. 2.

40 Fig. 5 is a cross section on the line 5—5 of Fig. 4.

Fig. 6 is a cross section on the line 6—6 of Fig. 4.

45 Fig. 7 is a perspective view of the pin supporting member.

Fig. 8 is a perspective view of the housing member.

Fig. 9 is a perspective view of my improved garment supporter with the pin and 50 its supporting member shown in the garment engaging position.

Similar reference characters designate 55 similar parts in the different views.

1 designates a housing member having a flat body portion and two tubular end portions serving as housing 2 and 3 and spaced

apart from each other and adapted to receive between them a portion of a garment, such as trousers 4, Fig. 4.

Longitudinally slidable in the housings 2 and 3 is a pin supporting member comprising a flat plate 5, provided adjacent to one end with means for attachment to wearing apparel, which means may comprise holes 6, through which extend threads 7, by which the plate 5 is attached to wearing apparel such as the tab 8, of a pair of suspenders 9, Figs. 1, 2 and 3.

The lower portion of the plate 5 has a lateral extension 9, which is provided with a longitudinal hole 10, through which extends a longitudinal pin 11, the upper end of which is pointed and adapted to be extended through the garment to be supported, such as the trousers 4.

The extension 9 is provided with a reversely turned lip 12, which extends over the hole 10 and bears against the lower end of the pin 11, so as to hold the latter in its operative position.

As shown in Figs. 4 and 7, the lower end of the pin 11 may be U-shaped, the short arm of the U being extended through a hole 13 provided in the extension 9.

The pin 11 is longitudinally movable with 85 the member 5 in the housing 2 to and from the garment engaging position, shown in Fig. 2, in which the pin 11 will have its free end extending into the housing 3.

For supporting the pin 11, a triangular tongue 14 may be punched from the plate 5 at right angles to the body of the latter, the outer end of the tongue being provided with an arcuate notch 15, in which the pin 11 is seated. The tongue 14 is of a length 90 sufficient to cause it to hold the pin 11 against the inner side of the housing 2, as shown in Figs. 4 and 6. The outer sides of the housings 2 and 3 may be V-shaped, as shown, so as to serve as a guide for the 100 pin 11.

In the operation of my invention, the plate 5 is slid downwardly to the open position shown in Fig. 3, in which position the pin 11 will have its upper portion drawn into the housing 2. The trousers 4 together with the shirt 16, indicated in dotted lines in Fig. 4, are then inserted between the housings 2 and 3, after which the plate 5 is drawn upwardly to the garment engaging position, shown in Figs. 2 and 4, in which position the pin 11 will extend 105 110

through the trousers 4, shirt 16 and into the housing 3. The pull of the trousers downwardly on the housing 2 will hold the latter against the extension 9, thus holding the 5 pin 11 in the housing 3, so that the trousers and shirt cannot be accidentally detached from the pin 11.

When it is desired to detach the supporter from the trousers and the shirt, the 10 plate 5 is forced downwardly to the release position shown in Fig. 3, thereby withdrawing the pin 11 from the trousers and shirt.

To yieldingly hold the plate 5 and member 1, in the release position shown in Fig. 15 3, so that the garment to be supported may be readily inserted between the housings 2 and 3, suitable means may be provided. For effecting this function, the plate 5 may 20 have punched and protruding from it a resilient tongue 17, which bears against the member 1 with a spring pressure, thereby affording yielding frictional engagement between the members 1 and 5, which yieldingly 25 holds said members from accidental sliding movement one upon the other.

I do not limit my invention to the structure shown and described, as many modifications, within the scope of the appended 30 claims, may be made without departing from the spirit of my invention.

What I claim is:—

1. In a garment supporter, two members, one having means for attachment to wearing apparel, said members being longitudinally slidible one on the other, one of the members having a housing, and a longitudinally disposed pin attached to and movable with the other member and adapted 35 to have its free end enter said housing, the pin carrying member being movable to and from a position in which the free end of the pin will be spaced apart from said housing, substantially as set forth.

2. In a garment supporter, two members, one having means for attachment to wearing apparel, said members being longitudinally slidible one on the other, one of the members having a housing, the other member 40 having a lateral extension, and a longitudinally disposed pin attached at its outer end to said extension and adapted to have its inner free end enter said housing, the pin carrying member being movable to and from a position in which the free end of the pin will be spaced apart from said housing, substantially as set forth.

3. In a garment supporter, two members, one having means for attachment to wearing apparel, said members being longitudinally slidible one on the other, said members having frictional means arranged to resist the sliding of one on the other, one of the members having a housing, and a longitudinal pin attached at one end to the 65

other member and adapted to have its other free end enter said housing, the pin carrying member being movable to and from a position in which the free end of the pin will be spaced apart from said housing, substantially as set forth. 70

4. In a garment supporter, two members, one having means for attachment to wearing apparel, said members being longitudinally slidible one on the other, one of the 75 said members having a resilient portion having frictional engagement with the other member for resisting the sliding movement, one of said members having a housing, and a longitudinal pin attached at one end to the other member and adapted to have its free end enter said housing, the pin carrying member being movable to and from a position in which the free end of the pin will be spaced apart from said housing, substantially as set forth. 80

5. In a garment supporter, two members, one having means for attachment to wearing apparel, said members being longitudinally slidible one on the other, one of the 90 members having two housings spaced apart and adapted to receive between them a portion of a garment, and a longitudinally disposed pin attached to and movable with the other member and slidable in one of said 95 housings and adapted to have its free end enter the other housing, the pin carrying member being movable to and from a position in which the free end of said pin will be spaced apart from said other housing, substantially as set forth. 100

6. In a garment supporter, two members, one having means for attachment to wearing apparel, said members being longitudinally slidible one on the other, one of the 105 said members having two housings spaced apart from each other and adapted to receive between them a portion of a garment, the other member having a lateral extension, and a longitudinal pin attached at one end to said extension and slidable in one of said 110 housings to and from a position in which it will enter the other housing, substantially as set forth.

7. In a garment supporter, two members 115 longitudinally slidible one on the other, one member having means for attachment to wearing apparel, one of said members having two housings spaced apart from each other and adapted to receive between them 120 a portion of a garment, and a longitudinal pin attached at one end to the other member and slidable in one of said housings to and from a position in which it will enter the other housing, one of said members having a resilient portion having sliding frictional engagement with the other member and arranged to yieldingly resist sliding movement of the members with respect to each other, substantially as set forth. 125 130

8. In a garment supporter, a member having two housings spaced apart from each other and adapted to receive between them a portion of a garment, a member longitudinally slidible in said housings, one of said members having means for attachment to wearing apparel, and a longitudinal pin attached at one end to the slidible member and longitudinally movable with said slidible member in one of said housings to and from a position in which its other end will extend into the other housing, substantially as set forth.

9. In a garment supporter, a member having two housings spaced apart from each other and adapted to receive between them a portion of a garment, a member longitudinally slidible in said housings, one of said members having means for attachment to wearing apparel, one of said members having a resilient portion having sliding engagement with the other member and arranged to yieldingly resist sliding movement of the members with respect to each other, and a longitudinal pin attached at one end to the slidible member and longitudinally movable therewith in one of said housings to and from a position in which its other end will extend into the other housing, substantially as set forth.

10. In a garment supporter, two members longitudinally slidible one on the other, one member having means for attachment

to wearing apparel, one of said members having two housings spaced apart from each other and adapted to receive between them a portion of a garment, the other member having a lateral extension provided with a hole therethrough and a lip, and a longitudinal pin extending through said hole and movable in one of said housings with said other member to and from a position in which the free end of said pin will extend into the other housing, the other end of said pin being overlapped by said lip, substantially as set forth.

11. In a garment supporter, two members longitudinally slidible one on the other, one member having means for attachment to wearing apparel, one of said members having two housings spaced apart from each other and adapted to receive between them a portion of a garment, the other member having a lateral extension provided with a hole therethrough and a lip, and a longitudinal pin extending through said hole and provided at one end with a head against which said lip bears, the pin being longitudinally movable with said other member in one of said housings to and from a position in which the other end of the pin will extend into the other housing, substantially as set forth.

In testimony whereof I have signed my name to this specification.

JOHN C. MABRY.
